[57] CLAIM

The ornamental design for a personal descent control fixture, as shown and described.

DESCRIPTION

FIG. 1 is a right side elevation of a personal descent control fixture showing my new design;

FIG. 2 is a top plan view thereof;

FIG. 3 is a front elevation thereof;

FIG. 4 is a rear elevation thereof; and,

FIG. 5 is a bottom plan view thereof.

The left side elevation is a mirror image of the side shown.
